UNITED STATES PATENT OFFICE.

WILLIAM A. McCOLLOUGH, OF LAMOILLE, IOWA.

STUBBLE-CUTTER.

No. 844,956.

Specification of Letters Patent.

Patented Feb. 19, 1907.

Application filed September 13, 1906. Serial No. 334,431.

To all whom it may concern:

Be it known that I, WILLIAM A. McCOLLOUGH, a citizen of the United States, residing at Lamoille, in the county of Marshall 5 and State of Iowa, have invented certain new and useful Improvements in Stubble-Cutters, of which the following is a specification, reference being had therein to the accompanying drawings.

10 This invention relates to stubble-cutters which are arranged for attachment to harvesting-machines or other transportable implements by which they can be drawn over the ground when in use; and it is primarily 15 designed to afford a strong, efficient, and simple means for attaching the drag-bar of such a cutter to the implement with which it is used. This means of attachment is especially susceptible of use with such a stubble- 20 cutter as is disclosed in my prior patent, No. 737,650, dated September 1, 1903, and in my copending application for patent on stubble-cutter, filed December 20, 1904, Serial No. 237,733, in which application the subject- 25 matter of this application was previously disclosed.

The details of construction and arrangement of parts contemplated by this invention are disclosed in the accompanying drawings, 30 forming part hereof, wherein is shown for purposes of illustration a preferable embodiment of the invention.

Like reference characters refer to corresponding parts in the several views of the 35 drawings, of which—

Figure 1 is a perspective view of the attachment as applied to a harvesting-machine or other carrier, it being necessary to show the latter in a fragmentary manner only. 40 Figs. 2 and 3 are detail sectional views of the forward coupling, and Fig. 4 is a detail view 45 of the link-supporting means.

Having more particular reference to the drawings, 5 designates a drag-bar and runner, the forward portion of which extends upwardly between and is secured to longitudinally-disposed beams 6 of the vehicle-frame. The securing means for this part comprise a bottom plate 7 and a top plate 8, perforated 50 centrally for the reception of a clamping-bolt 9, adapted, in coöperation with a nut 10, to draw the plates together and cause them to bind upon beams 6. The bottom plate just referred to has an enlargement or block 11 on its upper surface arranged to project into the

space intermediate the beams and contact with the inside faces thereof, the edges of the block being inclined to converge forwardly, whereby when the machine is backed when the implement is in engagement with the ground the resulting effect will be to wedge the block more tightly in place rather than tend to loosen the implement at this point of attachment. To perform a similar function, the top plate 8 has a pair of depending flanges 65 12 and 13, the former being substantially straight and the latter inclined forwardly and inwardly, whereby the draft on the machine and incidentally on the beams will tend to draw them through the clamping device, 70 and consequently by reason of the inclination just referred to of the flange more effectively wedge or bind the outer depending flanges 12 and 13 upon the outside edges of the 75 beams.

The rear end of the drag-bar or runner 5 is bent at a slight angle to the forward portion thereof, so that the same may occupy a substantially horizontal plane to contact with the ground and ride thereover, and to prevent penetration and embedding of this contact portion in the ground the same has a rather broad bearing-surface 14.

A pivot stub or pin 15 at the rear end of bar 5 passes freely through an eye 16 at the lower 85 end of a supporting-link 17, said eye being held upon the pin by a cotter-pin or its equivalent 18. The supporting-link just referred to is substantially straight as compared to the arched link of my former patent 90 and rather than extending upwardly and over the underframe of the vehicle is positioned therebeneath, as shown, whence it is secured to a beam 19 through the medium of loosely-interfitting eyes 20, the former being at the upper end of the link and the latter suspended from the beam 19 through the medium of a spacing-bar or wear-plate 21, through which and through apertures in said beam 19 separated arms 22 95 of said eye pass, the same being fastened in place by suitable nuts 23. By this arrangement greater play is allowed the link and drag-bar to overcome undue obstacles in the 100 path of travel of the cutter 24.

Having thus described my invention, what I claim as new, and desire to secure by Letters Patent, is—

1. In combination with a drag-bar, a coupling for pivotally securing the same in place 110

- comprising separated members, one having an inclined edge constituting a wedge, and means for forcing said members together.
2. In combination with a drag-bar, a coupling for pivotally securing the same in place comprising separated members, one having a surface projection and the other a depending inclined flange, and means for forcing said members together.
5. 3. In combination with a drag-bar, a coupling for pivotally securing the same in place comprising separated members, one having a surface projection and the other a depending flange, said flange and one edge of said surface projection inclining in opposite directions, and means for forcing said members together.
4. In combination with a drag-bar, a coupling for pivotally securing the same in place comprising separated members, one having a wedge-shaped surface projection and the other
- a depending flange the inclination of which is opposite to that of the edges of the projection, and means for forcing said members together.
- 25 5. The combination with a drag-bar and means for pivotally securing one end thereof, of a coupling for the other end of said drag-bar cooperating with said securing means to permit pivotal movement in the drag-bar, 30 said coupling comprising separated members, one having means for pivotal connection with the drag-bar and having a surface projection, and the other a depending flange, and means for forcing said members together.
- 35 In testimony whereof I affix my signature in presence of two witnesses.

WILLIAM A. MCCOLLOUGH.
